GRINDING-WHEEL DRESSING FIXTURE

Harry H. Gotberg and Joseph Silvagi, Detroit,
Mich., assignors to Colonial Broach Company,
Warren Township, Mich., a corporation of
Delaware

Application June 23, 1950, Serial No. 169,888

8 Claims. (Cl. 125—11)

1

This invention relates broadly to grinding-wheel dressing fixtures and more particularly to a fixture for dressing the involute side surfaces of gear grinding wheels.

Specifically, this invention is an improvement in the wheel dressing fixture disclosed in the Kopec Patent No. 2,321,825, dated June 15, 1943.

The patented fixture is adapted to grind the involute surfaces on opposite sides of a gear grinding wheel without necessity of moving the fixture when the dressing point is moved from one side of the wheel to the other. Fundamentally, the dressing device comprises a wheel dressing point carried by a parallelogram linkage, one pivot of which is fixed to a suitable support and another pivot of which has an extension constituting a follower for master cam members also mounted on the support. When the follower is moved along the cam surfaces the wheel dressing point of the device is caused to move in an involute path conforming to the desired shape of the grinding wheel.

In actual practice, however, prior art devices of the type hereinabove referred to are defective in operation because the wheel-dressing point is not maintained at all times in proper relation to the surface being ground. As a consequence, the point is presented differently to different parts of the surface; and since these points are irregular in shape, inaccuracies in the ground surface of the wheel result. These inaccuracies are, in turn, transferred to the gear ground by the wheel so that a faulty or imperfect gear is produced.

We have now discovered that the above defects in grinding-wheel dressers of the type shown in the Kopec patent can be obviated by keeping the wheel-dressing point exactly normal or perpendicular at all times to the surface being dressed, and have devised a modified construction for achieving and maintaining this relationship. When the dressing fixture is constructed according to the present invention, a substantially true involute surface is produced on the grinding wheel and uniform grinding of every wheel acted upon by the fixture is obtained. As a consequence, imperfect gears resulting from faulty dressing of the wheel used to grind the gears are eliminated.

From the foregoing it will be readily apparent that a primary object of the present invention is to reconstruct grinding-wheel dressing fixtures of the type shown in the Kopec patent supra so as to eliminate imperfections heretofore inherent in the fixture.

2

Other objects and advantages of the invention will be apparent during the course of the following description.

In the drawings forming a part of this specification and wherein like numerals are employed to designate like parts throughout the same:

Fig. 1 is a front elevational view of a grinding-wheel dressing fixture embodying the invention;

Fig. 2 is a fragmentary, vertical sectional view taken on the line 2—2 of Fig. 1;

Fig. 3 is a top plan view of the fixture;

Fig. 4 is a side-elevational view of the same;

Fig. 5 is an enlarged, fragmentary, vertical sectional view taken on the line 5—5 of Fig. 1;

Fig. 6 is a rear elevational view of the fixture;

Fig. 7 is a sectional view taken on the lines 7—7 of Fig. 1;

Fig. 8 is a vertical sectional view taken on the line 8—8 of Fig. 4;

Fig. 9 is a fragmentary sectional view taken on the line 9—9 of Fig. 1;

Fig. 10 is a fragmentary sectional view taken on the line 10—10 of Fig. 1;

Fig. 11 is a fragmentary sectional view taken on the line 11—11 of Fig. 1; and

Fig. 12 is an enlarged, fragmentary sectional view taken on the line 12—12 of Fig. 4.

In the drawings, wherein for the purpose of illustration is shown a preferred embodiment of the invention, the various moving parts of the fixture are mounted on an upright support 20 having a relatively large, horizontal base 22 provided with the usual adjusting pads 24. Immediately ahead of the support 20 on the base 22 is a flat supporting surface 26 on which a relatively small, upright, outboard support 28 is mounted and fastened securely in place by means of pins 30 and screws 32 (Fig. 1).

Mounted on the front of the support 20 is a pair of master cam members 34 and 36 having master cam surfaces 38 and 40 respectively of conventional shape for producing, in conjunction with other mechanisms hereinafter described, movement of a wheel-dressing point

along a true involute curve. More particularly, the master cams 34 and 36 are juxtaposed on the support 20 with the cam surfaces 38 and 40 side by side in confronting relation. At the inner bottom corners of the cams 34 and 36 are laterally extending tabs 42 and 44 respectively of reduced thickness and in overlapping relation as perhaps best shown in Figs. 5 and 8. A headed pivot pin 46 extends forwardly through the supports 20 and 28 and the tabs 42 and 44 are pivoted on the pins between the supports.

It is necessary to adjust the cams 34 and 36 angularly about pivot 46; and in order to hold them in a selected angularly adjusted position, each cam carries headed bolts 50 and 52 which extend through arcuate slots 54 and 56 respectively in the support 20. Washers 58 and 60 are provided on the projecting terminal portions of bolts 50 and 52, and wing nuts 62 and 64 also on the bolts are tightened against the washer to hold the cams solidly in selected adjusted positions. The heads of screws 50 and 52 preferably are countersunk flush with the forward surfaces of master cams 34 and 36 so that working parts hereinafter described in detail are free to move on the cams. It will be readily apparent in this connection that slots 54 and 56 are struck on arcs having the axis of pivots 46 as a center so that the cams 34 and 36 are free to adjust about the pivots. Sine bar buttons 66 and 68 (Fig. 6) are provided at the bottom outside corners of the master cams 34 and 36 as reference surfaces for use in angular adjustment of the cams.

Also mounted on the pivot pin 46 and in front of the master cams 34 and 36 are links 70, 72, 74, and 76 arranged generally in the form of a parallelogram and fastened together at the ends thereof by pivots 78, 80, and 82 disposed equidistantly apart. As perhaps best shown in Fig. 1, the parallelogram linkage is disposed upright in front of the master cams 34 and 36. In the interest of compactness links 70 and 74 are disposed in the same vertical plane, and the other two links 72 and 76 overlie links 70 and 74. The upper pivot 80 of the linkage has a rearward extension which defines a follower 84 for the master cams 34 and 36 and a handle 86 for manually moving the follower along the cam surfaces 38 and 40. This parallelogram linkage carries the wheel dressing point of the fixture and defines a pantograph which moves the dressing point in an involute path when the follower 84 is moved along one or the other of cam surfaces 38 and 40. In order to operate the linkage without interference from the supports, link 70 is mounted with the lower end thereof between the master cams 34 and 36 and the outboard support 28 (Fig. 5), and the pivoted end of the link 70 preferably is rabbeted as at 88. The lower end of link 72 also is mounted on the pivot 46 but forwardly of support 28, and the parts are held properly assembled by a set screw 90 which extends from one side of the link 72 into an annular groove 92 in pivot 46.

In order to hold the follower 84 pressed solidly against the cam surfaces 38 and 40 at all times during operation of the fixture, a pivoted supporting arm 94 is mounted on the pivot 46 behind the main support 20 and this arm has an outwardly offset terminal portion 96 which is connected to a pivoted lug 98 on the handle 86 by a spring 100. The supporting arm 94 is movable between the full-line and broken-line positions shown in Fig. 6 and is held securely in either one of the two positions by a lock pin 102 which extends through an opening in the arm and into suitably positioned sockets in the support 20. One end of a chain 104 is here shown fastened to the pin 102 by a screw 106, and the other end of the chain is fastened to any suitable or convenient part of the support 20 (not shown) to prevent the pin from being lost or mislaid when disengaged from the arm 94. A washer 108 on the follower 84 at the outer side of the master cams 34 and 36 co-

operates with link 74 in holding the follower on the cam surfaces.

In use, the arm 94 is moved to the full-line position (Fig. 6) when it is desired to move the follower 84 along the cam 36. When the arm is thus positioned, spring 100, which normally is maintained under tension, holds the follower 84 pressed downwardly against the cam 36 at all times during movement thereof along the cam surface 40. Conversely, when it is desired to move follower 84 along cam surface 38, the arm 94 is swung to the broken-line position (Fig. 6). In this position of the arm, spring 100 is disposed to press the cam follower 84 downwardly against cam 34 at all times during movement of the follower along cam surface 38.

In order to vary the ratio of the curve described by the dressing point and the curve of the master cam, an adjustable cross link 110 is mounted on the pantograph. Specifically, the cross link 110 is supported on opposite links 72 and 76 and parallel to links 70 and 74 by mountings 112 and 114. Pivots 116 and 118 fasten the cross link 110 on mounting blocks 112 and 114.

In order to adjust mounting 112 longitudinally along link 72, the latter is formed with a longitudinal slot 120 in which an adjusting screw 122 is mounted. One end of the screw 122 extends from the link 72, and the projecting portion thereof is provided with a manually operable handle 124. The mounting block 112 is formed at opposite sides thereof with flanges 126 and 128 which embrace the link 72 to guide the mounting block in its travel thereon. Between flanges 126 and 128 the mounting 112 is formed with a tongue or rib 130 which fits snugly in the slot 120 and threadedly receives the adjusting screw 122. The mounting block 112 is held securely but slidably on the link 72 by a retaining plate 132 which is fastened to the distal edge of tongue 130 by screws 134. It will be observed (Fig. 7) that retaining plate 132 extends laterally of the tongue 130 and that the projecting portions thereof travel in ways 136 and 138 to hold the block 112 on the link 72 while permitting the same to be freely adjustable on the link. A set screw 140 carried by and extending inwardly through flange 128 can be tightened against link 72 to hold the mounting block 112 in a selected adjusted position on the link. In the particular construction here shown by way of illustration, the pivot 116 is fixed to the cross link 110 and is rotatably associated with the mounting block by means of a cross pin 142 which interfits with a peripheral groove 144 in the pin.

The other mounting 114 is associated with cross link 110 and parallelogram link 76 in the same manner as mounting 112. As shown in Fig. 1, the parallelogram link 76 is formed with a longitudinal slot 146 and an adjusting screw 148 extends longitudinally therethrough. The screw 148 extends from one end of link 76 and the projecting end of the screw is provided with a manually operable handle 150. Mounting 114 has side flanges 152 and 154 disposed in embracing relation to link 76 and a middle rib 156 which fits snugly but slidably in slot 146. Adjusting screw 148 extends through and threadedly engages the rib 156 so that rotation of the screw moves the mounting longitudinally along link 76. A retaining plate 158 fastened to rib 156 by screws 160 holds the mounting block securely but slidably on link 76. Also it will be observed that pivot 118 press-fitted or otherwise fixed to cross link 110 is loosely journaled in the mounting

block 114 and held against longitudinal movement by a cross pin 162 which interfits with a peripheral groove 164 in the pin. A set screw 166 carried by the flange 152 of mounting 114 can be tightened against link 76 to hold the mounting block 114 in a selected adjusted position.

A chuck for the wheel dressing point is mounted on and longitudinally adjustable along the cross link 110. The chuck includes a mounting block 168 which is substantially identical to mounting blocks 112 and 114 hereinabove described. In this connection it will be observed that cross link 110 is formed with a longitudinal slot 170 and that a longitudinal adjusting screw 172 is provided in the slot. One end of screw 172 extends from cross links 110 and the projecting portion thereof is provided with a transverse manually operable handle 174. The mounting block 168 has side flanges 176 and 178 which straddle across link 110 and a rib 180 which fits snugly but slidably in the slot 170 and threadedly receives adjusting screw 172. The mounting block 168 is held on cross link 110 as in the mountings previously described by means of a retaining plate 182 which is fastened to the rib by a screw 184. The adjusting screw 172 is rotated to move mounting 168 along the link 110 and a set screw 186 carried by the mounting is tightened against the link to hold the mounting in a selected adjusted position.

The chuck also includes an arm 188 having a radial flange 190 at one end thereof which fits snugly but rotatably into a socket 192 provided in the face of mounting block 168. The arm 188 is held on the mounting block by a retaining plate 194 which fits snugly around the arm and is fastened securely to the block by a plurality of screws 196.

Arm 188 has a laterally offset bifurcated terminal portion 198 which carries the diamond dressing point 200. The latter is conventional, having a threaded casing 202 which is longitudinally adjustable relative to the arm 188 by means of a thumb nut 204 disposed between the terminal bifurcations of the arm.

According to the present invention, a block 206 is detachably fastened to the arm 188 by a spring-loaded detent 208, and adjacent corners of the block are connected to the distal ends of parallelogram links 70 and 72 respectively by control arms 210 and 212. In the form of the invention here shown by way of illustration, the inner adjacent ends of links 210 and 212 extend into slots 214 and 216 respectively provided in the upper corners of block 206 and the terminal portions disposed within the blocks are fastened by pivots 218 and 220. The outer distal ends of the control arms 210 and 212 are pivotally fastened to studs 222 and 224 respectively which in turn are fastened to the ends of links 70 and 72. In this latter connection it will be observed that studs 222 and 224 have reduced terminal portions 226 and 228 respectively which extend through longitudinal slots 230 and 232 in the control arms 210 and 212. Screws 234 and 236 hold the control arms 210 and 212 on the reduced terminal portions 226 and 228, and cross screws 238 and 240 hold the reduced terminal portions at the outer ends of their respective slots.

In order to position the point 200 for properly dressing the opposite involute surfaces of the grinding wheel, it is necessary to hold arm 188 in two positions 180° apart. To this end the arm 188 is provided at opposite sides thereof with openings 242 and 244 which receive the detent

208. When the detent 208 is retracted to disengage arm 188, the latter can be positioned either as shown in Fig. 1 or in a position 180° with respect thereto. In one position of the arm, detent 208 registers with opening 244 as perhaps best shown in Fig. 12, and in the other position of the arm the detent registers with opening 242.

For convenience, the block 206 preferably is made in two parts here designated 206a and 206b, the two parts being connected at one side thereof by a hinge designated generally 246. A latch bolt 248 is fastened to part 206a by pivot 250 at the side thereof remote from hinge 246, and the latch extends through a slot 252 in the corresponding side of part 206b. A nut 254 on the end of the latch bolt 248 is tightened to hold the two parts of the block together and around arm 188.

It of course is not necessary to remove block 206 entirely from the arm 188 when the latter is moved from one 180° position to the other. To accomplish this adjustment it is merely necessary to disengage the detent 208, rotate arm 188 to the desired position, and then again engage the detent with the aligned opening 242 or 244. There are occasions, however, as when it is necessary to adapt the device for dressing a different size grinding wheel, when it is necessary or desirable to substitute a larger or smaller arm 188. On these occasions the latch bolt 248 is disengaged to release mounting section 206b so that the latter falls away from the arm and automatically disengages the detent 208. Screws 196 are then removed to disengage retaining plate 194 and to permit complete removal of the arm 188.

In order to dress the periphery of the grinding wheel, a second dressing point 256 is provided, which point conveniently may be similar or identical to the dressing point 200 hereinabove described and is carried by a suitable chuck 258. The latter, in turn, is carried by and projects horizontally from a vertical slide 260 mounted in the guideway 262 of a vertical block 264 which is supported in proper relation with respect to the grinding wheel by a pair of arms 266 and 268. The supporting arms 266 and 268 are fastened to the upright base support 28 by screws 270 and to the mounting block 264 by screws 272. The chuck 258 is fixed on a rotatable shaft 274 which extends rearwardly through the slide 260 and through a vertically elongated slot (not shown) in the block 264. The rearwardly projecting end of shaft 274 carries a handle 276 that can be rocked back and forth to move the point 256 across the periphery of the grinding wheel here designated generally by the numeral 278.

In operation, the fixture is set up with the dressing points 200 and 256 disposed substantially as shown in Fig. 4 with respect to the grinding wheel 278. When thus positioned, the point 200 is positioned to dress the involute surface on one side of the wheel 278 and the point 256 is positioned to dress the periphery thereof.

To dress the periphery of the wheel it is merely necessary to rock the holder or chuck 258 about the axis of shaft 274 by means of handle 276. As the chuck is rocked in this manner, the wheel dressing point 256 is caused to travel back and forth across the periphery of the wheel and to dress the same.

In order to dress the involute surface of the wheel with the dressing point 200 in the position shown in the drawings, however, it is necessary to disengage control arm 210 from the

parallelogram linkage by removing screw 238. Thereafter, as the handle 86 is actuated to move the follower 84 along the left-hand cam surface 38, the parallelogram linkage acts through the crossbar 110 to move the point 200 along the involute surface of the wheel. Of particular significance in so far as the instant invention is concerned is the fact that during travel of the point 200 along the surface being dressed the control arm 212 pivots the chucks carrying the point to hold the latter substantially perpendicular at all times to the surface being dressed. In this manner, a truer involute surface is achieved than has been possible with prior art apparatus of this character. During the above operation spring 100 acts continuously in the manner described to hold the cam follower 84 against cam surface 38 and thus prevents any inaccuracies resulting from improper engagement of the follower with the cam surface.

Conversely, to dress the opposite involute surface of the wheel 278, it is merely necessary to reverse the dressing point 200 in the manner hereinabove described, move the spring arm 94 from the full-line to the dotted-line position, release control arm 212 from the parallelogram linkage, again engage control arm 210 to the linkage by reinserting fastening screw 238, and actuate handle 86 to move follower 84 along the right-hand cam surface 40. As the follower moves along the cam surface the parallelogram linkage is actuated in the manner hereinabove described to move the point 200 across the mentioned involute surface of the wheel, and during such travel of the dressing point the control arm 210 acts continuously to maintain the point exactly perpendicular to the surface being dressed. Also, it will be observed that during such operation, the spring 100 maintains the follower 18 pressed against the cam surface 40 to assure a true involute surface on the wheel.

Having thus described the invention, we claim:

1. A grinding-wheel dresser comprising a support; a master cam carried by said support; pivoted links forming a parallelogram having opposed pivots, one pivot being fastened to the support and the other pivot having an extension constituting a follower for said cam member; a cross link pivotally connected to and longitudinally adjustable along opposite links forming said parallelogram; a wheel-dressing device having a wheel-dressing point, a chuck carrying said point, and a mounting supporting said chuck for oscillation on said cross link; a control arm extending between the chuck and one of the links forming said parallelogram; pivots connecting opposite ends of said control arm to said chuck and said one link respectively, and means holding said control arm against independent longitudinal movement relative to said pivots, said control arm being operative to hold the dressing point continually normal to the surface being dressed as the follower is moved along the cam surface.

2. A grinding-wheel dresser comprising a support; a pair of master cam members carried by said support and having spaced confronting cam surfaces; pivoted links forming a parallelogram having opposed pivots, one fastened to the support and the other having an extension constituting a follower for said cam members; a cross link pivotally connected to and longitudinally adjustable along opposite links forming said parallelogram; a wheel-dressing device having a wheel-dressing point and a chuck carrying said point, the chuck being mounted for rotation on

5 and longitudinally adjustable along said cross link; control arms extending in opposite directions from said chuck and to the outer ends of adjacent links forming said parallelogram, pivots connecting the inner ends of said control arms to said chuck, pivots connecting the outer ends of the control arms to said adjacent links and means holding said control arms against independent longitudinal movement relative to said pivots, said arms being selectively disengageable from said links and operative to hold the dressing point continuously normal to the surface being dressed as the follower is moved along said cam surfaces.

3. A grinding-wheel dresser comprising a support; a pair of master cam members carried by said support and having juxtaposed cam surfaces; pivoted links forming a parallelogram having opposed pivots, one fastened to the support and the other having an extension constituting a follower for said cam members; a cross link pivotally connected to and longitudinally adjustable along opposite links forming said parallelogram; a wheel dressing device having a wheel dressing point and a chuck carrying said point, the latter being mounted for rotation on and longitudinally adjustable along said cross link; means detachably locking said chuck in each of two positions 180° apart; and control arms pivoted to said chuck and to adjacent links forming said parallelogram, said arms being selectively disengageable from said links and operative to hold the dressing point continuously normal to the surface being dressed as the follower is moved along said cam surfaces.

4. A grinding-wheel dresser comprising a support; a pair of master cam members carried by said support and having spaced confronting cam surfaces; pivoted links forming a parallelogram having opposed pivots, one pivot being fastened to the support and the other pivot having an extension constituting a follower for said cam member; a cross link pivotally connected to and longitudinally adjustable along opposite links forming said parallelogram; a wheel dressing device having a wheel dressing point and a chuck for said point, the chuck being mounted for oscillation on and longitudinally adjustable along said cross link; control arms at opposite sides of said chuck; means pivotally connecting the inner, adjacent ends of the arms to the chuck; and means pivotally connecting the outer, distal ends of the control arms to the parallelogram linkage, at least one end of each control arm being detachable to disengage the links from one of the members to which it is attached.

5. A grinding-wheel dresser comprising an upright support; a pair of master cams on said support having laterally spaced confronting cam surfaces; pivoted links forming a parallelogram having opposed pivots, one pivot being fastened to the support and the other pivot having a rearward extension disposed between said cam members and constituting a follower for said cam surfaces; a cross link pivotally connected to and longitudinally adjustable along opposite links forming said parallelogram; a wheel dressing device including a mounting carried by and longitudinally adjustable on said cross link, an oscillatable arm carried by said mounting and having an offset terminal portion, a wheel dressing point on the offset portion of said arm, and means holding the arm in selected rotatably adjusted position; control arms at opposite sides of said 70 oscillatable arms; means pivotally connecting the

outer ends of said control arms to said parallelogram; and detachable means providing pivots for the inner ends of said control arms and connecting the latter to said oscillatable arm.

6. A grinding-wheel dresser comprising a support; a pair of master cams on said support having laterally spaced confronting cam surfaces; pivoted links forming a parallelogram having opposed pivots, one of said pivots being fastened to the support and the other of said pivots having a rearward extension disposed between said cam members and constituting a follower for said cam surfaces; a cross link pivotally connected to and longitudinally adjustable along opposite links forming said parallelogram; a wheel-dressing device including a mounting carried by and longitudinally adjustable on said cross link, an oscillatable arm carried by said mounting and having an offset terminal portion, a wheel dressing point on the offset portion of said arm, an adjusting block loosely mounted on said arm, and means detachably fastening the oscillatable arm to said adjusting block; and control arms pivoted to opposite sides of the adjusting block at one side of said oscillatable arm and at opposite sides of said parallelogram.

7. A grinding-wheel dresser comprising a support; a pair of vertically disposed master cams on said support having laterally spaced confronting cam surfaces; pivoted links forming a parallelogram having opposed pivots, one of said pivots being fastened to the support and the other of said pivots having a rearward extension disposed between said cam members and constituting a follower for said cam surfaces; a cross link pivotally connected to and longitudinally adjustable along opposite links forming said parallelogram; a wheel-dressing device including a mounting carried by and longitudinally adjustable on said cross link, an oscillatable arm carried by said mounting and having an offset terminal portion, a wheel dressing point on the offset portion of said arm, an adjusting block loosely mounted on said arm, sockets spaced circumferentially around said arm, and a detent carried by the block movable into said sockets to hold the arm in selected rotatably adjusted position

in the block; and control arms pivoted to the adjusting block at opposite sides thereof and to opposite sides of the parallelogram linkage.

8. A grinding-wheel dresser comprising a support; a pair of master cams on said support having laterally spaced confronting cam surfaces; pivoted links forming a parallelogram having opposed pivots, one of said pivots being fastened to the support and the other of said pivots having a rearward extension disposed between said cam members and constituting a follower for said cam surfaces; a cross link pivotally connected to and longitudinally adjustable along opposite links forming said parallelogram; a wheel-dressing device including a mounting carried by and longitudinally adjustable on said cross link, an oscillatable arm carried by said mounting and having an offset terminal portion, a wheel-dressing point on the offset portion of said arm, an adjusting block loosely mounted on said arm, said adjusting block comprising hinged sections arranged in embracing relation to the arm and detachably fastened together on the arm, sockets at diametrically opposite sides of the arm, and a detent carried by the block movable into said sockets to hold the arm in selected rotatably adjusted positions in the block; and control arms at opposite sides of the wheel-dressing device, said control arms being pivoted to the adjusting block at opposite sides thereof and to opposite sides of said parallelogram linkage, said control arms being selectively disengageable from said parallelogram linkage and operative to hold the dressing point continuously normal to the surface being dressed as the follower is moved along said cam surfaces.
